Patented June 14, 1921.

Inventor:
Ulysses V. Garred.

by Edward J. Ridmond

Attorney.

UNITED STATES PATENT OFFICE.

ULYSSES VICTORIA GARRED, OF LOUISA, KENTUCKY.

MEMORANDUM ATTACHMENT FOR ALBUMS.

1,381,114.

Specification of Letters Patent. Patented June 14, 1921.

Application filed October 7, 1919. Serial No. 329,133.

To all whom it may concern:

Be it known that I, ULYSSES V. GARRED, citizen of the United States, residing at Louisa, in the county of Lawrence and State 5 of Kentucky, have invented a certain new and useful Improvement in Memorandum Attachments for Albums, of which the following is a specification.

This invention relates to improvements in 10 memorandum attachments for post-card or other picture albums and scrap-books, more especially for the loose leaves of such books.

The invention has for its object primarily to serve for readily and conveniently attaching or affixing the memorandum bearing means or tablet to the post-card or album.

A further object is to provide for compactly assembling the parts and simplifying 20 the construction and arrangement thereof.

A still further object is to provide for practically concealing the parts from view when not actuated and to facilitate the withdrawal and return to initial position of the 25 memorandum containing element.

A still further object is to carry out the aforesaid ends in an effective and inexpensive manner.

Other objects of the invention and those 30 above recited will be made fully apparent from the following description of the construction, arrangement and operation thereof.

The invention consists of certain instrumentalities and features of construction substantially as hereinafter more fully disclosed and defined by the appended claims.

The accompanying drawing illustrates the preferred embodiment, or one form, of 40 my invention wherein it will be understood that various changes and modifications may be made as to the detailed construction and arrangement of parts without departing from the spirit or scope thereof as covered 45 by the claims, and in which drawings:

Figure 1 represents a face view of a loose-leafed book embodying my invention with parts broken away.

Fig. 2 is a detached front view of the 50 memorandum bearing means, tablet or card, with its attaching member shown in dotted lines.

Fig. 3 is an edge elevation of the same, and

55 Fig. 4 is a perspective of a modification of the same.

Fig. 5 represents a vertical sectional view taken on the line $x-x$ of Fig. 6, and

Fig. 6 is an edge elevation of the showing disclosed more particularly by Fig. 5, 60 parts in both these views being broken away.

In carrying out my invention, I may employ it, as above indicated, in conjunction with a loose-leafed book as A, album, scrap-book, post-card, or provide in any other practical way for its utilization. The invention includes preferably a member 1, which may be a tablet, a card or other suitable instrumentality capable of having suitably indicated or produced memoranda thereon, as a 70 description, history or recital, usually in brief bearing upon the portrait or picture, post-card secured representation, etc. etc., which may be of interest and of use regarding the viewable subject-matter, all of 75 which, however, it will be appreciated is only incidental and not germane to the invention.

The member or memorandum tablet 1 is adapted to be suitably conformed to the 80 album leaf so as to be positioned or concealed out of sight under the picture 2 and yet said tablet be slideable inwardly and outwardly with respect to the picture as presently explained. Suitable means, as clips or 85 staples 3, suitably applied to the leaf, are provided for the attachment of the picture, the picture being preferably caught at its corners under the clips or staples, preferably as indicated.

The member or tablet 1 has at its bottom edge a manipulating tab 1^a and has suitably affixed, preferably, to its underside, near or at its upper edge, by gluing or otherwise, the upper end of a flexible strip 4, the opposite 95 or lower end of said strip being suitably affixed preferably, in like manner, to the leaf of the album or book near its upper edge, as clearly seen in dotted lines as at 5 in Figs. 1 and 2. The flexible strip 4 is 100 formed with a plurality of closely produced transverse creases or scores as at 6, extending practically throughout its entire length.

By reason of this arrangement and construction of parts it will be observed that 105 with the inserting or pushing of the memorandum inwardly, the creased flexible strip 4 will simultaneously be carried, in like manner, inwardly, causing the piling or folding thereof upon itself along the lines 110 of its creases or scores and thus effect through such piling or creasing action the

- crowding or wedging of the tablet into effectively secured position and without the aid of any other fastening or retaining instrumentality or means. Also that upon 5 simply pulling out the tab 1^a of the tablet 1 causing the withdrawal of the latter, the folded up flexible retaining strip will be lengthened out or extended as indicated in dotted lines in Fig. 3, thus requiring no further manipulation of parts for such withdrawal of said tablet or detaching of said strip to release it from the tablet or separating of the tablet and the retaining flexible strip for that purpose.
- 15 In the modification as disclosed by Fig. 4, I may form a memorandum tablet and its retaining or securing flexible member, designated as 1^b and 4^a respectively in a single or continuous piece.
- 20 From the foregoing presentation and accompanying illustration, it is believed that the construction and operation and utility and importance of my invention will be appreciated without further elaboration of the 25 same along those lines.

I claim:—

1. In a device of the type described, a photograph and its mount, a memorandum-tablet inserted therebetween, a flexible retaining member attached to said memorandum-tablet and the mount, said flexible member being coöperative therewith 30

through folding thereof upon itself intermediate said mount and said memorandum member, effecting the wedging of said memorandum-tablet in effective position. 35

2. In a device of the type described, a photograph and its mount, a memorandum-tablet inserted therebetween, a flexible retaining member attached to said memorandum-tablet and the mount, said retaining member having a plurality of closely arranged transverse creases or scores formed therein, whereby, as said tablet is moved inwardly, said flexible member will fold upon 40 itself intermediate said mount and said memorandum-tablet and wedge said tablet in effectively secured position.

3. In a device of the type described, a photograph and its mount, a memorandum-tablet inserted therebetween and having a transversely creased member in a continuous piece therewith, whereby as said tablet is moved inwardly, said transversely creased member will fold upon itself intermediate 50 said mount and said memorandum-tablet and wedge said tablet in secured position.

In testimony whereof I affix my signature in the presence of two witnesses.

ULYSSES VICTORIA GARRED.
